UNITED STATES PATENT OFFICE.

CHARLES H. BUCHHOLZ, DECEASED, LATE OF CLEVELAND, OHIO, BY ANNA BUCHHOLZ,
EXECUTRIX, OF CLEVELAND, OHIO.

FILLING-MACHINE.

1,268,923.

Specification of Letters Patent. Patented June 11, 1918.

Application filed March 20, 1915, Serial No. 15,751. Renewed April 13, 1918. Serial No. 228,505.

To all whom it may concern:

Be it known that I, CHARLES H. BUCHHOLZ, a citizen of the United States, residing at Cleveland, in the county of Cuyahoga and State of Ohio, have invented certain new and useful Improvements in Filling-Machines; and I do hereby declare the following to be a full, clear and exact description of the invention, such as will enable others skilled in the art to which it pertains to make and use the same.

This invention relates to automatic filling machines especially designed for filling containers with liquids and semi-liquids. The object of this invention is to provide a filling machine of the class set forth wherein the predetermined amount or quantity of liquid or semi-liquid to be contained or delivered is automatically determined by means of a balance which co-acts with a delivery faucet through intermediate mechanism so as to deliver and determine the amount delivered and to automatically close the faucet at the proper moment, this being accomplished accurately and positively, leaving no drip after the valve of the faucet is closed.

A further object of this invention is to so construct the mechanism that a minimum amount of pressure will be as effective as a maximum amount.

This invention consists in the parts and combination of parts, all of which will be hereinafter more fully set forth and claimed.

Figure I, is a view in side elevation representing a filling machine constructed according to this invention. In this view certain parts are removed to better disclose the interior or underlying mechanism. This view illustrates the mechanism as adjusted when the valve is open.

Fig. II, is a view in side elevation of the operating mechanism showing the position of the parts when the valve of the faucet is closed.

This invention is an improvement on the invention disclosed in my patent of May 4, 1915, No. 1,137,836, the improvement being comprised in a more sensitive auxiliary tripping device and mechanism whereby the valve of the faucet is closed.

In carrying out this invention as illustrated in the drawings presented I repre-

sents a tank for containing and supplying the material to be proportioned or canned. The tank 1 has, leading from its bottom, a delivery pipe 2 controlled by a cut-off valve 3. The outer end of the pipe 2 is provided with a valve controlled faucet 4 provided in turn with a valve 5 at its delivery mouth, said valve in turn being preferably spring pressed and having a vertical stem 6 projecting from its upper end to which the valve operating mechanism is connected. The stem 6 is provided with an adjustable collar 7 which in turn is engaged by a forked arm 8, said arm in turn being pivoted as at 9 to a standard 10 attached to the delivery pipe 2 and having an arm 11 extending in an opposite direction. Thus as the arm 11 is depressed the arm 8 is raised at its engaging end and the stem of the valve is raised thus opening the valve. In order to lock the valve in its open position a pivoted weighted lever 12 having a notch 13 is employed, this notched end engaging the lower end of a depending arm 14 which in turn is connected to and moves with the arms 8—11. The opening of the valve is accomplished by means of a vertically reciprocated rod 15 which engages the outer end of the arm 11 through the medium of an adjustable collar 16. The lower end of the rod 15 being attached to a foot treadle 17 and the rod being held in raised position by means of a spring 18, one end of which is attached to a bracket 19 which bracket also forms a guide for the rod 15 and the other end of said spring 18 being attached to the adjustable collar 19 secured at the lower end of the rod 15. The bracket 19 is secured to a standard 20 upon which the delivery pipe with the actuating mechanism is mounted, thus it will be seen that as the foot treadle 17 is depressed the valve of the faucet is opened and locked open allowing the container C to be filled.

Inasmuch as it is essential that after a predetermined amount of liquid or semi-liquid has been poured into the container C the valve should be automatically closed the following described mechanism is provided for this purpose:

21 represents a pivoted weighted dog, this dog 21 being pivoted as at 22 to a suitable bracket and provided with a suitable

5 weight 23 at its operating end. The weighted operating end is designed to strike a projecting pin P on the engaging end of the weighted lever 12 and release the catch or locking mechanism thus allowing the valve of the faucet to automatically close.

10 The weighted dog 21 is raised through the medium of an adjustable collar 24 on the rod 15, the collar 24 engaging the end 21' of the dog 21, thus depressing it at this end and raising it at its weighted end, all of which is accomplished as the valve of the faucet is opened by the depressing of the treadle 17.

15 In order to sustain the weighted end of the dog 21 in its raised position I provide on its end a notch N which is in turn engaged by a slightly over-balanced pawl 25 which is pivoted as at 26 and has an oppositely extending arm 27 provided with a projecting pin 28 which in turn is adapted to be engaged by the upper end of a rod 29 adjustably secured to the plate 30 of the balance, this plate 30 being directly beneath the faucet 4 and adapted to sustain the container to be filled. Thus as the plate 30 becomes over-balanced or moves downward as the container is filled or receives its pre-determined quantity, the upper end of the adjustable rod 29 engages the pin 28 pulling the arm 27 of the pawl 25 downward and disengaging the end of the said pawl from the notch N, allowing the weighted end of the dog 21 to strike the pin P thus in turn disengaging the weighted lever 12 from the lower end of the depending arm 14 and allowing the valve of the faucet to immediately close tightly.

20 The balancing device for determining the amount to be received by the containers to be filled may be of any suitable construction; the one illustrated being of the counter-balancing type and having a proportionately weighted member located on the platen opposite to the plate upon which the container rests.

25 In setting forth this invention I have described in detail the construction illustrated in the drawings but it is apparent both in structural detail and in assemblage and also in location of parts that changes may be made without departing from the invention.

30 Having thus described my invention what I wish to claim is:

35 1. A filling machine comprising means for automatically stopping the flow of fluid into a container to be filled, said means consisting of a faucet, a spring pressed valve in said faucet, a rocking arm pivotally attached to said machine, one end of said rocking arm engaging the valve stem of said faucet and the other end of said arm adapted to be operated to raise said valve stem, a pawl on said rocking arm adapted to engage a notch in an overbalanced pivotally

40 mounted dog, in combination with an auxiliary pivotally mounted weighted lever, the weighted end of which is adapted to be elevated, a notch in the end of said weighted lever adapted to be engaged by an overbalanced dog, and a balancing device provided with means for tripping said latter dog to allow said auxiliary pivotally mounted lever to trip aforesaid pivotally mounted dog to disengage said pawl from said dog for the purpose set forth. 70

45 2. A filling machine comprising a faucet, a balancing device provided with means for operating closing mechanisms in said filling machine, said mechanisms comprising a pivotally mounted arm provided with a pawl, one end of said arm engaging the valve stem of said faucet and the other end of said arm adapted to elevate said stem, a pivotally mounted arm provided with a notch to engage said pawl and an auxiliary weighted arm adapted to trip said aforesaid pivotally mounted arm for the purpose set forth. 80

50 3. A filling machine comprising a faucet, a valve and valve stem in said faucet, a balancing arm adapted to elevate the valve stem of said faucet, a pivotally mounted catch, a pawl on said arm adapted to engage said pivotally mounted catch, a balanced dog, a weighted arm adapted to be elevated and held in elevated position by means of said balanced dog, in combination with a tripping medium on said balancing device, said tripping mechanism adapted to trip said balanced dog for the purpose set forth. 90

55 4. A filling machine comprising a faucet, a rocking arm, a valve stem adapted to be elevated by means of said rocking arm, said rocking arm provided with a pawl adapted to be engaged by a balanced catch, a pivotally mounted weighted arm adapted to be elevated simultaneously with the movement of the rocking arm, a pivotally mounted dog adapted to engage said weighted arm in said elevated position, in combination with a balancing device and means on said balancing device for tripping said pivotally mounted dog for the purpose set forth. 100

60 5. A filling machine comprising a balance, a shut-off for controlling the supply of fluid to be contained in a container, a valve in said shut-off, a means for holding said valve open, in combination with a weighted lever for engaging the means for holding said valve open and an auxiliary weighted lever for tripping said first mentioned lever, said latter lever being actuated upon the completion of the extreme downward motion of said balance. 110

65 6. A filling machine comprising a balance, a shut-off for controlling the supply of fluid to be contained in a container, a valve in said shut-off, means for holding said valve open, in combination with a weighted lever 120

for engaging said means for holding said valve open and an auxiliary weighted lever for tripping said first mentioned lever, said latter lever being provided with means for suspending it above the engaging lever and means for tripping said suspending means, all substantially as and for the purpose set forth.

Signed at Cleveland in the county of Cuyahoga and State of Ohio this 17th day 10 of March 1915.

CHARLES H. BUCHHOLZ.
